MEDICINAL VAPORIZER

Douglas W. Anderson, Palatine, Ill., assignor to Hanks-craft Company, Reedsburg, Wis., a corporation of Wisconsin

Application May 7, 1958, Serial No. 50,792

Term of patent 14 years

(Cl. D83—1)

Fig. 1 is a perspective view of a medicinal vaporizer embodying my new design;

Fig. 2 is a right side elevational view thereof;

Fig. 3 is a front elevational view thereof;

Fig. 4 is a top plan view thereof;

Fig. 5 is an enlarged fragmentary vertical cross section taken through the side of the vaporizer substantially along the line 5—5 in Fig. 2;

Fig. 6 is an enlarged fragmentary horizontal cross section taken through the side of the vaporizer substantially along the line 6—6 in Fig. 2; and

Fig. 7 is a similar fragmentary cross-sectional view taken substantially along the line 7—7 in Fig. 2.

I claim:

The ornamental design for a medicinal vaporizer, substantially as shown.
